UNITED STATES PATENT OFFICE.

JAY G. SWAB, OF BALDWIN, NEW YORK, ASSIGNOR TO TENSION ENVELOPE CO. INC.,
OF BROOKLYN, NEW YORK, A CORPORATION OF NEW YORK.

FASTENER FOR ENVELOPES AND THE LIKE.

Application filed August 10, 1925. Serial No. 49,493.

My invention relates to fasteners adapted to serve for holding the flap of an envelope or similar article. Heretofore, fasteners of this character have been made by stamping from metal a single piece containing a central eyelet portion having oppositely extending fingers, and this was attached to the envelope by placing the eyelet through the body of the envelope and flattening the eyelet. Sometimes a stiffening member or reinforcement of heavy stock was applied to the body of the envelope around the eyelet to prevent the latter from pulling out. The projecting fingers remained close to the body of the envelope until the latter was put into use, whereupon the fingers were bent outwardly and passed through the aperture in the flap of the envelope, and then the fingers were pressed down to secure the flap in place in such manner that it could be reopened by again bending up the fingers. In order to facilitate the application of the fasteners to the envelope and in order to reduce the cost of manufacture by eliminating the expensive operation of drawing the eyelet from the flat metal, another form of fastener was devised in which pointed prongs were formed from the central portion of the blank by cutting and bending the metal. While this latter form of fastener served to reduce the cost of manufacture and facilitated the application of the fastener to the envelope, there was a tendency for the fastener to bend or buckle on a line passing between the adjacent prongs. An attempt has been made to avoid this by widening the central portion of the fastener and providing a double set of prongs, thereby increasing the amount of metal used to prevent this buckling operation. This, however, increases the cost of manufacture, owing to the additional metal used. The object of my present invention is to secure all of the advantages of the prong construction in fasteners of this character, and at the same time eliminate the tendency to buckle.

In the drawing forming part of this application,

Figure 1 is an edge view of my improved fastener attached to an envelope,

Figure 2 is a sectional view taken on the line 2—2 of Figure 3, but showing the fastener attached,

Figure 3 is a face view of the fastener before it is attached, and

Figure 4 is a sectional view taken on the line 4—4 of Figure 3.

The parts are shown on an enlarged scale in the several views.

In the drawing I have shown a piece of metal 1 which is blanked and formed by suitable machinery to form the oppositely extending fingers 2 which project from the central circular portion 3 from which latter the prongs are formed. This central portion of the metal is cut at four places in radial lines, and the metal is forced at right angles to the plane of the blank to provide the pointed prongs 4. Preferably, these prongs are four in number as described, although the invention is not limited to the employment of this particular number of prongs. It will be apparent that as these prongs are formed from the central portion of the blank, the latter is weakened on a line passing between the prongs at opposite sides, where the stock merely consists of the annular portion from which the prongs extend. In order to prevent the blank from buckling across this line, I have provided ribs 5 and 6 which may be formed simultaneously with the blanking operation and they are made by forcing the metal upwardly in the form of an arch, as shown at 5 in the drawing. While a single rib may be formed entirely around the opening created by the prongs, I prefer the construction shown in the drawing wherein there are two separate ribs 5, 6 extending partially around the prong opening at opposite sides, the ribs terminating at points 7. The object of this is to leave the metal flat at the point where the fingers 2 bend in relation to the middle portion of the blank, in order that when the fingers are bent back and forth in the operation of closing and opening the envelope the metal will not bend sharply at a fixed line as would occur if the rib extended entirely around the central openings.

In Figure 1, I have shown a fastener secured to an envelope body, the prongs 4 being passed through the body of the envelope, and turned over against the inner surface of the body. In preparing the envelope for closing, the fingers 2 will be bent upwardly or away from the body of the envelope in order to be passed through the

aperture in the flap. Where the device is made according to the preferred form shown in the drawing, the metal will not form a sharp bend at the base of the fingers, but rather a gradual bend will take place at some line adjacent the space between the ends 7 of the opposite ribs. After the fingers have been inserted through the flap they are bent back against the outer surface thereof in the usual manner. If the fingers are again bent to release the flap (not shown) and the operation is repeated a number of times, the fastener will permit a greater number of bending operations before the metal cracks, than if the ribs were carried across the base of the fingers. In the operation of bending the fingers back and forth, in the type of fastener having a central eyelet, the eyelet itself prevents the central portion of the fastener from buckling, whereas in the form of fastener heretofore proposed and containing prongs in place of the eyelets, there was a tendency for the fastener to buckle on a line passing between the opposite pairs of prongs. In the present case, however, the central portion of the fastener

is stiffened by the presence of the ribs 5, 6 in order to prevent this buckling operation in the absence of the eyelet. By this combination of elements I am able to secure all of the advantages of the prong construction without increasing the amount of metal to any appreciable extent and at the same time eliminate the tendency of the fastener to buckle.

Having described my invention, what I claim is:

A fastener of the class described comprising a plate having a central portion and fingers projecting therefrom for the purpose set forth, said central portion being cut and formed to provide a plurality of pointed prongs disposed around a central aperture, said central portion of the fastener having raised ribs formed therein at opposite sides of and in concentric relation with said prongs, said ribs terminating at such points as to leave the said plate flat from the said central opening outwardly along said fingers.

Signed at the city, county and State of New York, this 17th day of July, 1925.

JAY G. SWAB.
